CLAIM

An ornamental design for a soap dish, as shown and described.

DESCRIPTION

FIG. 1 is a top, front and right side perspective view of a soap dish showing my new design;

FIG. 2 is a top, front and right side perspective view thereof, with the broken-line disclosure of a soap bar being for illustrative purposes only and forming no part of the claimed design;

FIG. 3 is a top plan view thereof; and,

FIG. 4 is a right side elevational view thereof, the left side being a mirror image of that shown.
